UNITED STATES PATENT OFFICE.

OLIVER S. WRIGHT, OF MASONTOWN, PENNSYLVANIA, ASSIGNOR TO NEPTUNE MANUFACTURING COMPANY, OF MASONTOWN, PENNSYLVANIA, A CORPORATION OF DELAWARE.

SHARPENING DEVICE.

Application filed November 27, 1925. Serial No. 71,613.

This invention relates generally to devices for sharpening cutting implements such as knives, chisels, shears, etc., and more particularly to a type embodying two groups of freely-revolvable discs with circumferential cutting edges arranged in overlapping relation to form an intervening sharpening crotch through which the article being sharpened is adapted to be drawn.

Amongst the objects of my invention are to enable, in connection with a sharpening device of the type referred to, stagewise sharpening, i. e. from an initial coarse trim or take off of the metal, and through intermediate graduated stages, to a final honing action, as may variously be required depending entirely on the nature of the article being sharpened, as well as upon the condition of its edge; and to secure the above desiderata in a sharpener more especially intended for table use.

Other objects and advantages will be manifest from the detailed description hereinafter of the typical embodiment of my invention illustrated by the accompanying drawings, whereof Fig. I is a view showing the sharpening device in plan;

Fig. II, a side elevation of the same; and Fig. III, an edge view of the two cooperating disc groups on a larger scale than shown in the preceding figures.

With reference to these illustrations, the two groups of cutting discs are comprehensively designated by the numerals 5, 6 respectively, and, as shown, the components of each of said groups are mounted for free rotation upon axes 7 fixedly supported in the base member 8. These axes 7 are suitably spaced to predetermine a slight overlap of the cutting edges of the respectively corresponding discs, and with resulting formation between the two groups, of a sharpening crotch 9 through which the blade of the article to be sharpened is drawn. In addition to free rotation on the axes 7, the discs may be also allowed a slight amount of lateral play, their proper spacing being however always maintained by appropriate concentric filler washers 10, interposed between them. It is to be especially noted that the cutting discs of each of the groups 5, 6 are graduated in size, that is to say, they diminish successively in diameter uniformly and

symmetrically relative to the central disc 11, which, in each instance, is the largest. It will also be observed that the discs of each group 5, 6 differ in the character of their cutting edges, the outer ones designated 12 having sharp cutting edges, the intermediate discs 13, rounded edges, preferably roughened by longitudinal corrugations as conveniently indicated in Fig. III, while the central disc 11 has but a plain smooth rounded edge. As a consequence of the variation in the diameters of the discs of both groups 5, 6, the intersection of the corresponding discs 11—11, 12—12 and 13—13 occur in different planes vertically so that the sharpening crotch 9 is highest in the middle and lowest at the outer ends. As a result of this gradation, it is possible to employ corresponding pairs of the discs separately and thus to effect stagewise sharpening. For example: if a knife blade, in being drawn through the sharpening crotch 9, is properly inclined to the horizontal in one direction or the other, the end discs 12—12 may be employed to effect a rough cut or trim. With a little less inclination of the blade, either corresponding pair of the intermediate discs 11 may be employed to smooth the rough cut or trim previously made; and by holding the blade perfectly horizontal, the central pair of discs 11 may be selected to effect a final honing action.

Referring now more in detail to the base 8, it will be observed that the same has a central hollow raised portion 15 that completely houses the two cutting disc groups 5—6 except for a comparatively-narrow central opening 16 which affords access to the sharpening crotch 9 between the overlapping edges of said disc groups. The side walls 17—18 of the approach to the opening 16 are sloped as shown in Fig. II, preferably at different angles. By this construction, implements with a single bevel edge,—such as chisels, plane blades, shear blades, etc.—may be guided and supported at the proper angle while drawing them through the sharpening crotch 9 as indicated in dotted lines in Fig. II, the difference in the slope of the walls 17, 18 permitting selective choice in accordance with differences in the bevel angle of implements of the kind mentioned. As shown in Figs. I and II, the

- base 8 is comparatively broad and covers a substantial area so as to be sufficiently stable and heavy for table use without necessitating permanent securing of the device.
- 5 At each end of the central raised portion 15 which houses the disc groups 5—6, the weighted base 8 is provided with lugs 19 that afford rests 20 within which carving knives and the like may be inserted for 10 temporary support after sharpening.

Having thus described my invention, I claim:

- 15 1. A sharpening device of the character described comprising a multiplicity of freely-revolvable cutting discs, said discs having varied cutting edges and being graduated as to diameter so as to be capable of selective employment by changing the angle at which the article being sharpened is drawn relative 20 to them.
- 25 2. A sharpening device of the character described comprising a multiplicity of freely-revolvable cutting discs, said discs differing in the character of their circumferential cutting edges, and being graduated with regard to diameter so as to be capable of selective employment in effecting stagewise sharpening by varying the angle at which the article being sharpened is drawn relative 30 to them.
- 35 3. A sharpening device of the character described comprising two groups of freely-revolvable discs having contrasting peripheral edges and overlapping to form a sharpening crotch between them, the co-operative discs in the respective groups diminishing in diameter symmetrically to opposite sides of central discs so that any corresponding pair of discs of said groups may be selectively employed by varying the angle at which the article being sharpened is drawn through the crotch aforesaid.
- 40 4. A sharpening device of the character described comprising two groups of freely-revolvable discs with their cutting edges overlapping to form a sharpening crotch between them, the discs in the respective groups differing in the character of their cutting edges and diminishing in diameter symmetrically to opposite sides of central discs so that any corresponding pair of discs of the two groups may be selectively employed by varying the angle at which the article being sharpened is drawn through the crotch aforesaid.

- 45 5. A sharpening device of the character described comprising two groups of freely-revolvable discs with their cutting edges overlapping to form a sharpening crotch between them, the discs of the respective groups diminishing in diameter symmetrically to opposite sides of central discs so that any corresponding pair of discs of the two groups may be selectively employed by varying the angle at which the article being sharpened is drawn through the crotch aforesaid.

6. A sharpening device of the character described comprising two groups of freely-revolvable discs, said discs having cutting edges of contrasting finish and overlapping to different extents with formation of a sharpening crotch between them, whereby any corresponding pair of said discs may be selectively employed by changing the angle at which the article being sharpened is drawn through the sharpening crotch.

7. In a sharpening device of the character described, the combination of two groups of freely-revolvable discs having cutting edges of diverse cross-section and overlapping to form a sharpening crotch between them; and a weighted supporting base completely housing the two disc groups except for opposed medially located narrow openings affording access to the sharpening crotch aforesaid.

8. In a sharpening device of the character described, the combination of two groups of freely-revolvable discs having cutting edges of contrasting cross-section and overlapping to form a sharpening crotch between them; and a weighted supporting base completely housing the disc groups except for medially located narrow openings affording access to the sharpening crotch aforesaid, the approach to each said opening having sloping side walls to assist guidance and support at the proper tilt, of cutting implements having a single beveled edge.

9. In the sharpening device of the character described, the combination of two groups of freely-revolvable discs having cutting edges of contrasting cross-section and overlapping to form a sharpening crotch between them; and a weighted supporting base with a central hollow raised portion completely housing said disc groups except for opposed medially located bevel-edged openings affording access to the sharpening crotch aforesaid, said base also having, at opposite sides of its raised portion, vertical projections affording temporary support for carving knives and the like.

In testimony whereof, I have hereunto signed my name at Masontown Pa. this 31st day of October 1925.

OLIVER S. WRIGHT.
